Inventor:
James Worth Haggard

UNITED STATES PATENT OFFICE.

JAMES W. HAGGARD, OF PORTLAND, OREGON.

SADDLE-HORN.

SPECIFICATION forming part of Letters Patent No. 595,567, dated December 14, 1897.

Application filed April 13, 1896. Serial No. 587,435. (No model.)

To all whom it may concern:

Be it known that I, JAMES WORTH HAGGARD, a citizen of the United States, residing in the city of Portland, county of Multnomah, and 5 State of Oregon, have invented a new and useful Improvement in Saddle-Horns for Riding-Saddles, of which the following is a full, clear, and exact description, to wit:

The nature and object of my invention consist in providing a saddle-horn, solid or hollow, with disk or projection, ribs or flanges, legs or forks combined and united so as to give strength and resist force or strain as applied to saddle-horns as used in riding-saddles. 10 I attain these objects by means of the mechanism illustrated in the drawings filed with my application for Letters Patent herein, in which—

Figure 1 is a perspective view of the saddle-horn comprising my invention. Fig. 2 shows a front view of the saddle-horn. Fig. 3 exhibits a view of the saddle-horn, together with the disk or projection, ribs or flanges, legs or forks claimed by me to be an improvement in saddle-horns, with other parts of riding-saddles, including side bars and wooden forks in front and rear of the saddle-horn in riding-saddles.

Similar letters refer to similar parts throughout the several views.

The saddle-horn is made of malleable iron or other material, and is made solid or hollow, as desired, and of any convenient size and proportion of parts.

In the figures of the drawings the several parts are represented as follows: A' is the pommel of the saddle-horn; B, the neck of the saddle-horn; C C, legs or forks of the saddle-horn; D, the rib or flange in rear of the saddle-horn; E, the rib or flange in front of the saddle-horn; F, disk or projection in front of the saddle-horn; G G G G, the side bars of the riding-saddle; H H, the wooden fork in front of the saddle-horn; I I, the wooden fork 40 in rear of the saddle-horn; J, groove in wooden fork H H, in which is fitted the rib or flange E; K, mortise or space on top of wooden fork H H to receive the disk or projection F; A A A A, holes of convenient size in the legs or forks 45 of the saddle-horn C C to insert screws or nails for fastening together the wooden fork I I, saddle-horn, and wooden fork H H; b b, screw

or nail holes for inserting screws or nails; c c, screw or nail holes for fastening disk or projection F to wooden fork H H; d d d d d d, 55 screws or nails for fastening the respective parts together, as shown in the drawings.

It is intended that the legs or forks of the saddle-horn C C, when adjusted to the riding-saddle, may be either in a vertical position 60 or at any desired angle deviating therefrom and with each leg or fork resting on a side bar G G G G, respectively, as shown in the drawings.

In Fig. 3 of the drawings the wooden fork 65 I I is fitted to and screwed fast to the saddle-horn, Fig. 1.

The saddle-horn, Fig. 1, as used in riding-saddles is to be placed contiguous to the wooden fork H H and firmly fastened to it by 70 means of screws or nails passing through the disk or projection F into the holes c c in the wooden fork H H, and also by means of screws or nails passing through the wooden fork I I, the legs or forks of the saddle-horn C C, into 75 the wooden fork H H. It is intended also that the parts of the saddle-horn, either solid or hollow, which I claim to be an improvement thereof and thereto—to wit, the legs or forks C C, the flange in the rear of the saddle-horn D, the rib or flange in front of the saddle-horn E, with the disk or projection F— 80 are to be made or cast with and inseparable from the saddle-horn, and thus combined is designed and intended to resist force or 85 strain from whatsoever source or direction it may emanate or be applied, prevent the saddle from flattening or spreading, combine strength, lightness, durability, symmetry, 90 simplicity, economy, and preservation of space in its construction as well as novelty of adjustment and attachment to all kinds of riding-saddles as applied thereto.

I am aware that prior to my invention saddle-horns have been made with the neck of 95 the saddle-horn hollow and also with the saddle-horn fastened to the saddle or wooden fork thereof by one or more divisions of the saddle-horn at its lower extremity made into flat or leaf-like disks or divisions nailed or 100 screwed to the saddle or wooden fork of the same; but I am not aware that any saddle-horn has ever been invented with the whole thereof made hollow, or with legs or forks ex-

tending in the same or nearly the same direction longitudinally with the neck of the saddle-horn beneath the pommel thereof, or with the flattened surface and width of the 5 legs or forks C C so arranged as to resist force or strain and to prevent a saddle from flattening or spreading, as is shown in said drawings, or with a rib or flange D in the rear of the saddle-horn, and with disk or projection F and 10 rib or flange in front of the saddle-horn E, and saddle-horn attached to or fastened to riding saddles, combined as set forth in said drawings.

What I do claim as my invention, and hereby desire to secure by Letters Patent, is— 15

An improvement in saddle-horns, as applied to riding-saddles, combining as set forth above, saddle-horn hollow, disk or projection, F, with rib or flange, E, in front of saddle-horn: rib or flange, D, in rear of saddle-horn: with legs 20 or forks of saddle-horn, C, C, substantially as is hereinabove set forth and described.

JAMES W. HAGGARD.
